UNITED STATES PATENT OFFICE.

JOSEPH E. AUE, OF NEW YORK, N. Y., ASSIGNOR TO DE LA VERGNE MACHINE COMPANY, OF NEW YORK, N. Y., A CORPORATION OF NEW YORK.

REGULATING APPARATUS FOR INTERNAL-COMBUSTION ENGINES.

No. 867,565.

Specification of Letters Patent.

Patented Oct. 8, 1907.

Application filed August 26, 1903. Serial No. 170,810.

To all whom it may concern:

Be it known that I, JOSEPH E. AUE, a citizen of the United States, residing at the borough of the Bronx, city of New York, county of New York, and State of New York, have invented certain new and useful Improvements in Regulating Apparatus for Internal-Combustion Engines, of which the following is a specification, reference being had therein to the accompanying drawing.

10 My invention consists in regulating apparatus for internal combustion engines, and relates broadly to that type in which is employed a fluid-fuel or gas pumping apparatus or compression chamber distinct from the engine proper or engine combustion chamber, 15 and communicating with a source of fluid-fuel and supplying the engine proper or engine combustion chamber with the fluid-fuel or gas required for combustion.

In such broad relation to the art, my invention has for its object, to regulate the out-put power and speed 20 of such internal combustion engines, uniformly economically and without impairment of combustion or explosion, by regulating with greater nicety, uniformity and economy than has heretofore been attained, the amount of fuel delivered to the engine proper or engine 25 combustion chamber by the fuel pumping apparatus or fuel-compression chamber during each working cycle of the engine.

My invention is more particularly intended, however, as an improvement on the regulating apparatus 30 of that particular example of the above defined type, which is known as the Koerting engine and to which my invention is particularly well adapted; and it is in this particular application and embodiment that my invention is specially described and illustrated in the 35 following specification and in the accompanying drawings.

It has heretofore been recognized that an ideal solution of the problem of regulation in engines of the type defined, would be attained if the phase or instant 40 of operation of the valves controlling communication with the fluid-fuel pumping apparatus could be automatically varied or shifted by suitable connection with an engine-actuated governor proper so as to vary the amount of fuel transferred from the pumping apparatus 45 to the engine proper for each cycle of its operation. And it has heretofore been further conceived that such regulation might be effected specifically by causing such a shifting or variation of the valve phase to vary in turn the effective displacement of the pumping apparatus, for instance in such manner that gas 50 would be returned freely from its compression chambers to the source of fluid-fuel during the variable first part of the compression period of such chambers and would then be discharged or delivered to the engine

proper during the remaining variable portion of such compression period. But the foregoing ideal method of regulation has not been heretofore realized because the unavoidable friction in the valves themselves has offered a difficulty which has not been surmounted. This difficulty resides in the fact that in every case 60 where the automatic governor proper is called upon to directly shift the phase of the valves, it is requisite in order to effect that end, to exert a force sufficient to actually shift the valves themselves against the very considerable friction which always resists their motion. 65 Therefore a very considerable speed fluctuation has been found necessary to develop in the governor proper the required amount of shifting effort required to control the valves directly, and as a result, engines thus governed have been disposed to "hunt" or "race" 70 badly.

Most specifically, it is the object of my present invention, to attain in an operative apparatus the ideal system of regulation formulated in the foregoing. To that end my invention provides valve-operating mechanism of adequate force and power to move the valves positively through their proper cycle, but controlled and varied in its phase or instant of operation by independently operative phase-controlling mechanism including the governor proper and moving in the discharge of its controlling function with negligible friction. The entire regulating system is thereby made very sensitive and responsive to slight variations in the speed of the engine, while the governor proper varies and determines the phase of the valves without 85 being required to exert sufficient force to shift them in opposition to their own friction.

I will now describe the construction of regulating mechanism illustrated in the accompanying drawings and will thereafter point out my invention in claims. 90

Figure 1 is a sectional diagram of the entire regulating system, and shows some features of actual construction. Fig. 2 is a side elevation of a preferred form of the valve-operating and phase-controlling mechanism. Fig. 3 is a plan view of the entire engine. Fig. 4 is a section on the plane *a*, *a*, of Fig. 2, showing a valve proper and part of its operating and controlling mechanism. Figs. 5 and 6 are respectively longitudinal and transverse sections through the compression chamber and the inlet valve mechanism at 100 the crank end of the working cylinder of the engine, and show a modification in the valve mechanism.

The main cylinder 1 of the engine proper, is provided at either end with a suitable compression chamber 2. A double-acting piston 5 reciprocates in the cylinder, propelling the engine by means of the usual piston rod 53 and connecting rod 90. The inclosed space at either end of the piston constitutes a working

- or expansion chamber of the engine. An exhaust port 8 communicating with the interior of the cylinder at a point midway between its ends, is passed and opened by either end of the piston in either extreme 5 of its stroke, and is thereby made common to both expansion chambers. The air and gas pumps 13 and 14 comprise double-acting pistons 47 and 48 respectively, in tandem by a common piston rod 49 and reciprocating in their respective air and gas cylinders 61 and 10 62. Both pistons are propelled by the engine by means of the piston rod 50, connecting rod 79 and crank 80 mounted on the main shaft 65. Each piston divides its respective cylinder into two compression chambers, marked 9 and 10 in the air pump, and 11 15 and 12 in the gas pump. The air and gas compression chambers are provided near their outer ends with ports 16 and 18 respectively, leading through the cylinder walls and controlled respectively by semi-rotating or rocker valves 20 and 19 of substantially 20 cylindrical form and disposed respectively in valve casings 96 and 72, with their axes at right angles to the axes of the pump cylinders. The valve-casings are formed integrally with the pump cylinders and the rocker-valves are provided with valvular ducts, 25 I shaped in transverse section and extending longitudinally to the entire transverse width of their respective cylinder ports.

Midway between the two rocker-valves, each pump cylinder is provided with an inlet or inlet duct also 30 controlled by the valves and marked 86 and 87 in the air and gas pumps, respectively, and communicating respectively with the outer air and with a source of gas or other fluid-fuel. The source of fluid-fuel is not shown on the drawings, but since the gas pump 35 is intended to communicate with such a source directly through its inlet 87, this inlet may itself be regarded as a source from which the pump may draw its fuel, for the purposes of this description and the claims which follow.

40 Each pump cylinder is provided at its outer ends with two outlets or discharge ducts, 15 and 17 in the air and gas pumps respectively, and each discharge duct or passage is also controlled by its adjacent rocker-valve.

45 Each expansion chamber of the engine is provided with an air conduit, and a gas conduit, 6 and 7 respectively, communicating with the expansion chamber through a common inlet port or passage 3 leading into it through the upper wall of its end compression 50 chamber 2 and controlled by an inlet valve 4 of the puppet type. These air and gas conduits lead to the expansion chambers of the engine from the outlets or discharge ducts 15 and 17 of the air and gas pumps respectively. Suitable check valves 97, 98, 99 and 55 100 are interposed in the conduits near the ends thereof.

All the rocker-valve casings are closed at either end by end plates, such as 71 and 72 shown in Fig. 4, which 60 illustrates the mounting of one of the rocker-valves 19 of the gas pump, and the mechanism of the air pump rocker-valves is similar to that of the valves 19 in the following respects: Their operating stems 66 project through the front end-plate 72 and are provided at their inner ends with clutches 67 locking with corresponding clutches 68 mounted on the adjacent ends

of the respective rocker-valves. The clutches are longitudinally separable and are held in engagement by studs 70 inserted through the rear end-plates 71 and abutting upon corresponding pins 69 fixed upon the ends of the rocker-valves opposite their respective 70 clutches. This organization permits the removal of the rocker-valves from the rear ends of their casings without disturbing their operating stems 66 and the mechanism co-operating therewith.

The operating stems of the air pump rocker-valves 75 are provided at their outer ends with fixed rocker-arms 21 connected by a pitman rod 22. Corresponding rocker-arms 44 are loosely mounted upon the outer ends of the operating stems of the gas pump rocker-valves, so as to be freely rotatable with respect to the stems. These rocker-arms 44 are also 80 united by a pitman 24, and the two sets of rocker-arms are arranged in line and connected by another pitman 23 between their adjacent rocker-arms. As illustrated in the drawings, the pitman rods 24 and 25 85 are made in one rod. All the rocker-arms are caused to rock or oscillate in unison by a common connection to the engine, consisting in a fourth pitman rod 25 connected between the rocker-arm 44 nearest the engine and a short link 103 connected in turn to a lever 90 26 mounted upon one end of the rock-shaft 76 actuated by still another lever at its opposite end which is driven by a connecting rod 29 actuated by an eccentric strap 88 co-operating with an eccentric on the main shaft.

95 Valve-operating levers 43 are fixedly mounted on the outer ends of the operating stems of the gas pump rocker-valves and outside the rocker-arms 44. These valve-operating levers 43 comprise diametrically opposed upper and lower locking and retraction arms 100 respectively. Retraction springs 46, connected to respective retraction arms, tend always to place or retain the rocker-valves in their outlet or discharge positions, i. e., such angular positions as will afford communication through their respective gas compression chambers and the outlet ducts 17 at their respective ends of the gas pump cylinder and leading to corresponding expansion chambers of the engine. In such outlet or discharge positions, the rocker-valves will close communication between their respective compression chambers and the inlet duct 87 110 leading from the source of gas.

The loose rocker-arms 44 of the gas pump valve gear are provided with outwardly extending valve-operating pins or projections 45 which engage the 115 valve-operating levers 43 and move them and their rocker-valves in opposition to the retraction springs and into their inlet positions i. e., the angular positions which will afford communication between their respective compression chambers and the inlet duct 120 87 but will close communication between the compression chambers and their corresponding expansion chambers of the engine. In the inlet positions of the valve-operating levers, their locking arms are engaged and locked by the retaining arms 35 of their 125 respective valve triggers. These triggers are pivotally mounted, and provided diametrically opposite their retaining arms 35 with trip arms 34 which are engaged by the trip pins 42 mounted upon and extending outwardly from the trip levers 32 which are 13

also pivotally mounted just inside the valve triggers and concentrically therewith upon common release-controlling eccentrics 33. Suitable retaining springs 75 tend always to move the triggers and their respective trip levers in such relative angular directions as to bring the trip pins 42 and the trip arms 34 into engagement and thus retain them. These springs also act in the proper directions to retain their respective triggers in locking engagement with the corresponding valve-operating levers until forcibly disengaged therefrom by the trip pins 42. In the preferred construction shown in Fig. 2, the retaining springs 75 are circular springs of wire located between the triggers and their respective trip levers, making one complete turn around the hubs thereof, and each secured at one end to the trip lever by passing through a hole therein and bearing at its other end upon a suitable pin fixed in the trigger.

The release-controlling eccentrics 33 are pivotally mounted upon studs 73 inserted into bosses formed on the pump cylinder casting just above the valve casings. Depending rocker arms 85 are secured upon the release-controlling eccentrics inside the triggers and trip levers, and are connected by respective transmitting rods 37 with respective diametrically opposite pins 39 inserted in a common wrist plate 40 pivotally mounted at its center. The wrist plate is provided with a rocker-arm 38 connected by a transmitting rod 41 and other suitable mechanism to the centrifugal governor proper 52, whereby the governor in its variations effects corresponding variations in the angular position of the wrist plate, and hence also effects corresponding variations in the angular positions of the release-controlling eccentrics 33 connected to the wrist-plate. Since the mechanism involved in these variations may be comparatively light and of comparatively negligible friction, it is apparent that such variations may be effected by very slight fluctuations in the speed of the governor proper and the engine.

The trip levers 32 are united by a rod 31 and caused to oscillate in unison by motion imparted through a connecting link 104 from the rocker arm 27. The rocker arm 27 is secured to the outer end of a hollow rock-shaft or bushing 77 mounted within a journal bracket 78 extending from the cross-head guide of the pumps. Upon the inner end of the hollow rock-shaft is fixed another rocker arm 63 actuating the rock-shaft and itself actuated by a connecting rod 28 upon the further end of which is an eccentric strap 89 co-operating with an eccentric on the main shaft of the engine.

The phase relation between the valve-operating mechanism and the pump pistons, is such that all the rocker-valves are in or passing through their inlet positions or phase during the expansion or suction periods of their respective compression chambers, while the rocker-valves of the air pump are in their discharge or outlet phase during the compression periods of their respective compression chambers. But the rocker-valves of the gas pump are retained by their respective triggers in their inlet positions during variable first portions of the compression periods of their respective compression chambers, and are only held in their discharge or outlet positions or phase during variable latter portions of

such compression periods and after having been moved into such discharge positions by their retraction springs upon being released by their respective triggers. When the valves are thus retracted, the valve-operating pins engage the valve-operating levers 43 and act as stops for their valve-operating levers.

The engine inlet or admission valves 4 are operated by valve levers 91 which are connected by cam rods 92 to the cam followers 59 actuated by the valve cams 60 mounted upon and driven by the cam shaft 51 suitably geared to the main shaft to the engine. The governor proper is also driven by the cam shaft through a bevel gearing 93. Suitable ignition plugs 95 may be inserted into the compression chambers 2 of the engine proper, through the holes provided for that purpose.

The pump crank 80 is in advance of the main crank of the engine, by about ninety degrees, and the pump pistons lead the engine piston 5 by a corresponding amount. The cycle of operations, with respect to either expansion chamber of the engine proper, and its corresponding inlet valve, inlet port, air and gas conduits, check valves therein, and pump compression chambers with their respective valve mechanism, etc., etc., is as follows: During its compression stroke, the engine piston compresses an explosive mixture of gases into the clearance space or compression chamber 2 at the end of the expansion chamber. The compressed mixture is ignited by a suitable igniting plug, explodes or burns rapidly, and by its expansion impels the piston forward until the exhaust port 8 is opened, whereupon a portion of the products of combustion rapidly escapes and the pressure in the expansion chamber is reduced substantially to that of the atmosphere. At this instant the inlet valve 4 is opened and an initial influx of air from the air pump compression chamber, through the air conduit 6 and inlet port 3, advances toward the exhaust port and carries before it the remaining products of combustion, thereby expelling a still further portion of the products of combustion through the exhaust port. The initial influx or installment of unmixed air is followed by a secondary influx of air and gas simultaneously from their respective pump compression chambers and through their respective conduits and the common inlet port 3, where they mix as they enter the expansion chamber. This secondary influx pushes the initial installment of unmixed air before it still further toward the exhaust port, thereby expelling all but a small portion of the still remaining products of the combustion of the preceding cycle. The exhaust port then closes, the engine piston 5 proceeds on its next compression stroke, the inlet valve 4 is again closed, and the contents of the expansion chamber are again compressed into the clearance space. The explosive portion of such contents, *i. e.*, the secondary or mixed installment of fluid, remains nearest the inlet end of the chamber and is separated from the remaining small portion of inert products of combustion, by the initial installment of pure air. The explosive mixture is then ignited and expanded again, and the foregoing cycle is again enacted, the compression-chambers of the pumps having meantime taken in another charge of fluid during their expansion or suction period. During the early part of the compression stroke or period in either compression chamber of the gas pump, while its respective rocker-valve is in the inlet position or

phase, the gas of course flows from the compression chamber back through the inlet duct toward the source of supply. It is not until the trip pin 42 engages the trip arm 34 of the trigger and causes its retaining arm 5 to disengage the valve-operating lever 43, that the retraction spring 46 moves the valve into its outlet or discharge position, and the compression commences to discharge the remaining portion of its contents into the gas conduit 7 and thence into the expansion chamber of the 10 engine. The precedence of the initial influx of unmixed air into the expansion chamber, is due to this lag in the phase of gas influx.

It is apparent that the power of the explosive impulses and the out-put power of the engine must depend upon and vary with the quantity of explosive mixture introduced into the expansion chamber and ignited therein during each working cycle. Such quantity of course depends upon and varies with the amount of gas delivered at each stroke by the gas pump 15 compression chamber to its gas conduit and expansion chamber of the engine, and the amount thus delivered is exactly proportional to the effective displacement of the gas pump piston, which effective displacement is determined and varied by and with the phase or 20 instant of retraction of the rocker-valve, *i. e.*, the phase or instant in the stroke of the gas pump piston at which the rocker-valve is reversed so as to turn the discharge from its compression chamber into its outlet duct, in lieu of the inlet duct. Thus the out-put power of the 25 engine varies correspondingly with variations in the phase or instant of retraction, and this phase or instant of retraction is automatically varied and determined by the governor proper, in the manner which I will now describe. It will be noted that the general location 30 of the center of either release-controlling eccentric 33 is above the stud 73, about which it oscillates through a short arc, so that the principal rectilinear component of its movement is horizontal throughout its entire angular variation. And since the eccentric 35 constitutes the pivot for its respective trigger and trip lever, it is apparent that the common axis of these levers is thereby subjected to considerable horizontal displacement relative to their ends which respectively engage the valve-operating lever 43 and connect with 40 the pitman rod 31. Such a horizontal displacement of their common axis relative to such ends of the levers obviously varies the angular positions of the trigger and trip lever relative to one another when the actuating pitman rod 31 is in any given position, prior to 45 engagement of the trip pin 42 with the trigger, and thereby varies the position or phase of its motion in which the trip lever will engage the trigger and release therefrom the locking arm of the valve-operating lever 43. Thereby the governor proper 52, in its variations, 50 effects corresponding variations in the phase or instant of retraction, and ultimately correspondingly varies the power of the engine in accordance with the demand.

Since the governor proper only operates against 55 negligible friction, it is sensitively responsive to slight speed fluctuations and effects most uniform regulations. The regulation is also thoroughly economical, because fuel is only supplied in proportion to the demand. Also, the effective scavenging accomplished by the 60 initial influx or installment of air, and the fact that

this initial installment separates the residual products of combustion from the new explosive mixture, insures non-pollution of the new mixture and non-impairment of ignition.

It is the function of the check valves 97 and 98 in 70 the air and gas conduits, to prevent transference of the fluid from one conduit to the other through their common inlet ports 3 and during the intermissions between the periods of admission to the expansion chambers of the engine. These check valves may be dispensed 75 with however, and the same end may be accomplished by employing the modified inlet valve mechanism shown in Figs. 5 and 6, in lieu of the ordinary inlet valve shown in Figs. 1 and 3. In the modified inlet valve mechanism, the main inlet puppet valve 4^a is 80 supplemented by an auxiliary puppet valve 4^b located above the main valve and mounted upon an upwardly extending hollow valve stem through which the valve stem of the main valve passes concentrically. The main valve is seated in the inlet port proper, while the 85 auxiliary valve engages an annular seat upon the cylindrical wall between the gas and air conduits, thereby preventing communication from one to the other. The hollow stem of the auxiliary valve is mounted in a suitable guide. Both valve stems are 90 provided with springs tending always to move their valves into engagement with their seats and retain them there. A three-armed valve lever 54 is fulcrumed between opposing webs of a suitable frame which also forms an upper guide and spring pocket for 95 the main valve stem. The extreme ends of two arms 55 and 56, of the valve lever, are rounded and slotted as indicated and straddle the main valve stem. They bear down respectively upon a collar pinned on the main valve stem, and upon the top of the auxiliary 100 valve stem. The motion required to open the valves is transmitted to the valve lever through a cam rod 57 connecting the third arm of the lever with a cam follower 59; actuated by the valve cam 60 which is mounted upon the cam shaft 51 of the engine. The cam rod 105 is retained in operative position by a swing guide 58 as shown.

It is the function of the check valves 99 and 100, located in the air and gas conduits near the main inlet valves, to prevent the air and the gas, respectively, 110 under pressure in the conduits, from flowing back into the pump chambers when the inlet valves are opened, and thus to prevent the flow of air and gas into the pumps which would have to be pumped out again into the conduits by the operation of the pumps.

It is obvious that various modifications may be in the construction and combination of parts with in the spirit and scope of my invention.

What I claim and desire to secure by Letters Patent is:

1. In regulating apparatus for internal combustion engines, the combination of an engine proper, a fluid-fuel pump connected with the engine and with a source of fluid-fuel a regulating valve controlling communication between the pump and the source of fluid-fuel and operative from a position of opening such communication to a position of closing such communication and vice versa, a valve-operating mechanism for periodically moving the valve into one of such positions, a second valve-operating mechanism for periodically moving the valve into the other of such positions, and automatic governing mechanism actuated by the engine and periodically determining

the phase or instant of operation of the second valve-operating mechanism.	
2. In regulating apparatus for internal combustion engines, the combination of an engine proper, a fluid-fuel pump connected with the engine and with a source of fluid-fuel, a regulating valve controlling communication between the pump and the source of fluid-fuel, valve-operating mechanism in constant phase relation to the working cycle of the engine for periodically moving the valve into a position of opening such communication, retractive valve-operating mechanism in variable phase relation to the working cycle of the engine for moving the valve into a position of closing such communication, and automatic retraction-governing mechanism actuated by the engine and periodically determining the phase or instant of retraction.	10
3. In regulating apparatus for internal combustion engines, the combination of a reciprocating engine proper, a fluid-fuel pump in constant phase relation to the engine and connected through suitable fluid conduits with the engine and with a source of fluid-fuel, a regulating valve controlling communication between the pump and the engine and operative from a position of opening such communication during the compression stroke of the engine to a position of closing such communication and vice versa, valve-operating mechanism for periodically moving the valve into one of such positions, retractive valve-operating mechanism for moving the valve into the other of such positions, and automatic retraction-governing mechanism actuated by the engine and periodically determining the phase or instant of retraction.	15
4. In regulating apparatus for internal combustion engines, the combination of an engine proper, a fluid-fuel pump connected by suitable fluid conduits with the engine and with a source of fluid-fuel, a regulating valve controlling communication between the pump and the engine, valve-operating mechanism for periodically moving the valve into a position of closing such communication, retractive valve-operating mechanism for moving the valve into a position of opening such communication, and automatic retraction-governing mechanism actuated by the engine and periodically determining the phase or instant of retraction.	20
5. In regulating apparatus for internal combustion engines, the combination of an engine proper, a fluid-fuel pump communicating with the engine and with a source of fluid-fuel, a check valve interposed between the pump and the engine, a regulating valve controlling communication between the pump and source of fluid-fuel and operative from a position of opening such communication to a position of closing such communication and vice versa, valve-operating mechanism for moving the valve into the other of such positions, and in variable phase relation to the first said valve-operating mechanism and automatic retraction-governing mechanism actuated by the engine and periodically determining the phase or instant of retraction.	25
6. In regulating apparatus for internal combustion engines, the combination of an engine proper, a fluid-fuel pump communicating with the engine and with a source of fluid-fuel, a regulating valve controlling communication between the pump and the engine and source of fluid-fuel and operative from a position effecting communication between the pump and engine but non-communication between the pump and source of fluid-fuel to a position effecting communication between the pump and source of fluid-fuel but non-communication between the pump and engine and also operative reversely from the second of such positions to the first of such positions, valve-operating mechanism for periodically moving the valve from one of such positions of opening such communication to a position of closing such communication and vice versa, valve-operating mechanism for periodically moving the valve into one of such positions, retractive valve-operating mechanism for moving the valve into the other of such positions, and automatic retraction-governing mechanism actuated by the engine and periodically determining the phase or instant of retraction.	30
7. In regulating apparatus for internal combustion engines, the combination of an engine proper, a fluid-fuel pump communicating with the engine and with a source of fluid-fuel, a regulating valve effecting communication between the pump and the engine and source of fluid-fuel, valve-operating mechanism for periodically moving the valve into a position effecting communication between the pump and source of fluid-fuel, retractive valve-operating mechanism for moving the valve into a position effecting communication between the pump and engine, and automatic retraction-governing mechanism actuated by the engine and periodically determining the phase or instant of retraction.	35
8. In apparatus for regulating internal combustion engines, the combination of an engine proper comprising a plurality of working or expansion chambers, a fluid-fuel pump, comprising a plurality of compression chambers communicating with respective expansion chambers of the engine and also communicating with a source of fluid-fuel, regulating valves controlling communication between respective compression chambers and their corresponding expansion chambers and the source of fluid-fuel and adapted to assume positions affording communication between the compression chambers and their corresponding expansion chambers and the source of fluid-fuel or positions affording communication between the compression chambers and source of fluid-fuel but effecting non-communication between the compression chambers and their corresponding expansion chambers, common valve-operating mechanism for periodically moving all the valves into one of the positions aforesaid, common valve-retracting mechanism for moving all the valves into the other of such positions and variable in its phase or instant of operation relatively to the cycle of the pump, and automatic retraction-governing mechanism actuated by the engine and periodically determining the instant or phase of retraction.	40
9. In apparatus for regulating internal combustion engines, the combination of an engine proper comprising a plurality of working or expansion chambers, a fluid-fuel pump comprising a plurality of compression chambers connected with respective expansion chambers and communicating with source of fluid-fuel, an air pump, comprising a plurality of compression chambers also connected with respective expansion chambers and communicating with a source of air, regulating valves controlling communication with respective compression chambers of the fluid-fuel pump and movable into positions affording communication between the compression chambers and the source of fluid-fuel but effecting non-communication between the compression chambers and their respective expansion chambers or positions affording communication between the compression chambers and their corresponding expansion chambers but effecting non-communication between the compression chambers and the source of fluid-fuel, air pump valves controlling communication with respective air pump compression chambers and likewise movable into either of two positions respectively affording communication between the compression chambers and source of air but effecting non-communication between the compression chambers and their corresponding expansion chambers or affording communication between the compression chambers and their corresponding expansion chambers but effecting non-communication between the compression chambers and the source of air, common valve-operating mechanism actuated by the engine and alternately moving the air pump valves into each of such positions and periodically moving the regulating valves into one of their positions aforesaid, common valve-retracting mechanism for moving all the regulating valves into the other of such positions and variable in its phase or instant of retraction as related to the working cycle of the fluid-fuel pump, and common automatic retraction-governing mechanism actuated by the engine and periodically determining such phase or instant of retraction of all the regulating valves.	45
10. In regulating apparatus for internal combustion engines, an engine proper comprising a plurality of working or expansion chambers, fluid-fuel pumping apparatus actuated by the engine and comprising a plurality of compression chambers, air pumping apparatus actuated by the engine and comprising a plurality of compression chambers, two independent fluid-fuel and air conduits communicating	50

- with each expansion chamber through a common valve-controlled inlet port or passage into such chamber, such conduits leading respectively from one of the fluid-fuel compression chambers and from one of the air compression chambers, and for each air compression chamber an air valve controlling its inlet and the outlet to its respective air conduit and movable to either of two positions respectively opening the inlet but closing the outlet or opening the outlet but closing the inlet, and for each fluid-fuel compression chamber a regulating valve-controlling its inlet and the outlet to its respective fluid-fuel conduit and movable to either of two positions respectively opening such inlet but closing such outlet or opening such outlet but closing such inlet, common valve-operating mechanism actuated by the engine and moving the air valves into each of their two positions alternately while moving the regulating valves periodically into one of their two positions, common valve retracting mechanism moving the regulating valves into the other of their two positions and variable in its phase or instant of operation relatively to the cycle of the valve-operating mechanism, and common automatic retraction-governing mechanism actuated by the engine and periodically determining such instant or phase of retraction. 55
11. In regulating apparatus for internal combustion engines, the combination of an engine proper comprising a double acting piston and a working or expansion chamber at either end thereof, air and gas pumps comprising compression chambers at opposite ends of double acting pistons arranged in tandem on a common piston rod and actuated by the engine, independent air and gas conduits communicating with each expansion chamber of the engine proper through a common valve-controlled inlet port or passage and containing check valves and leading from respective air and gas compression chambers respectively, oscillating air valves controlling communication with each air compression chamber, oscillating regulating valves controlling communication with each gas compression chamber, valve-operating devices actuated by a common connection to the engine and moving the air valves so as to transfer communication with their respective compression chambers from the inlets of such chambers to the outlets of such chambers leading to their corresponding air conduits and also reversely moving the air valves, but moving the regulating valves only so as to transfer communication with their respective compression chambers from the outlets of such chambers connecting with corresponding gas conduits to the inlets to such chambers, valve retracting springs connected with the regulating valves and exerting a continuous effort to move the valves so as to reversely transfer communication with their respective compression chambers from the inlets thereof, valve-locking devices opposed to the retracting springs and retaining the regulating valves in their positions of outlet communication, unlocking or tripping devices actuated by a common connection to the engine and co-operating with locking devices to unlock or release the regulating valves and thus permit their retraction, and release-controlling mechanism acting in conjunction with the locking and unlocking devices to vary the phase or instant of unlocking relative to the cycle of the valve-operating devices and actuated by a governor proper driven by the engine. 60
12. In regulating valve mechanism for internal combustion engines, the combination of a regulating valve movable into either of two operative positions, periodically operative valve-operating mechanism placing the valve in one of its positions, valve-retracting means for moving the valve into the other of its positions, a valve-retaining device mounted to oscillate upon a movable pivot and engaging a suitable co-operating member connected to the valve and thereby retaining the valve against the effort of the valve-retracting means, a periodically oscillating valve-releasing device mounted upon the movable pivot with the valve retaining device and co-operating therewith when in definite angular relation thereto to release the valve therefrom and permit the valve to be retracted, and release-controlling mechanism operating to vary the position of the movable pivot and thereby vary the angular relation of the valve-retaining device and the valve-releasing device so as to effect a variation in the instant or phase of release and retraction. 65
13. In regulating apparatus for internal combustion engines, the combination of an engine proper, a fluid-fuel pump connected by a suitable fluid conduit with the engine proper, a regulating valve in control of communication between the pump and the engine and having a normal bent to open condition, valve closing means co-operative with the regulating valve mechanism to close the regulating valve periodically, and speed controlled retraction-governing means controllable by the engine speed and arranged to release the valve mechanism to permit it to assume its normal open condition. 70
14. An internal combustion engine comprising an engine cylinder, a double acting engine piston in the cylinder dividing the cylinder into two combustion chambers, a source of fluid fuel, trip-valve mechanism including two valves in control of communication between the respective combustion chambers and the source of fluid fuel, and an engine driven speed governor in control of the tripping phase or instant of the valve mechanism. 75
- In testimony whereof, I have affixed my signature in presence of two witnesses.
- JOSEPH E. AUE.
